PLAY SUIT

Anne M. McElreath, Wadley, Ga.

Application December 10, 1956, Serial No. 44,130

Term of patent 3½ years

(Cl. D3—17)

Fig. 1.

Fig. 2.

Fig. 1 is a front view of a play suit showing my new design, and

Fig. 2 is a rear view of the play suit.

The essential features of my design are shown in solid lines on the drawing.

I claim:

The ornamental design for a play suit, as shown and described.
